UNITED STATES PATENT OFFICE.

WILLIAM W. WINGER, OF WOLCOTT, INDIANA.

LAUNDRY MACHINE.

Application filed January 16, 1922. Serial No. 529,766.

My invention relates to driving and operating mechanism for laundry machines and has for its object the production of a simple, durable and less expensive construction than any heretofore made, as well as a more efficient mechanism, one which is compact in its arrangement and adjustment of parts so that the entire structure will not occupy more space than will be occupied by the ordinary tub and bench.

It is an object of my invention to so construct the same that it may be arranged to operate with a single tub and wringer; or with a plurality of tubs and wringer; to operate the washing mechanism alone, or to operate the washing and wringer mechanisms simultaneously.

A further object of my invention is to provide mechanism for agitating the washer, the operation of the agitating mechanism being controlled by levers adapted to be thrown into and out of engagement with the driving rod as required during the operation of the machine, and to reduce the number of gears and other mechanism heretofore required for transmitting motion to the operating mechanism, and for regulating the operation of the different parts of the machine.

In the accompanying drawings I have illustrated what I now consider the preferred form of my invention, in which I have shown an embodiment of the essential features of my improvements and in these drawings:—

Fig. 1 is an end elevation of my machine, Fig. 2 is a side elevation of the same, Fig. 3 is a bottom plan view of the oscillating mechanism,

Fig. 4 is a bottom plan view of a modified form of oscillating mechanism,

Fig. 5 is a plan view of the gear and cam mechanism,

Fig. 6 is a sectional view taken on line 6—6 of Fig. 5,

Fig. 7 is a detail of the oscillating mechanism,

Fig. 8 is a plan view of a collar and projecting connecting member co-acting with the cam mechanism,

Figs. 9 and 10 are respectively a plan view and side elevation of a modified form of said ring used when two tubs are being operated simultaneously,

Fig. 11 is a top plan view of a portion of the supporting frame with the tub removed,

Fig. 12 is a detail taken on line 12—12 of Fig. 4,

Fig. 13 is a fragmentary top plan view of the tub with a portion broken away. 60

Referring to the drawings, 12, represents a bench or support of any suitable form and construction to sustain the mechanism hereinafter described.

Mounted within this frame is a motor 13, 65 which has the necessary connection with any suitable source of driving power. A pulley 14 is driven by this motor and has a belt transmission 15 from said motor to a pulley 16, mounted upon a shaft 17, which is supported in brackets 18 attached to said frame 12. A sprocket 19 is mounted upon the shaft 17. Supported in bearings 20 is a horizontal shaft 21 which carries a corresponding sprocket 22. A sprocket chain 23 connects 70 and transmits motion to the two sprockets 19—22 as shown more clearly in Figure 2.

A bevel gear 24 is carried by the shaft 21 near the opposite end thereof, this gear being in operative engagement with the corresponding gear 25. Formed integrally with the gear 25 is a cam ring 26 disposed eccentrically with respect to gear 25. Surrounding the cam 26 is a ring 27, if one tub is used (or ring 28, if two tubs are used.) 85

The cam rings are provided with a projecting attaching member 29 to which is secured a horizontally extending rod 30, which may be fixed in place by a cotter pin or otherwise, the attachment being made 90 through either of the openings in said attaching member 29. Having engagement with the opposite end of the rod 30 is a rod 31 which extends at right angles thereto and is pivotally attached at the opposite side of 95 the supporting frame to the lever 47, which in turn is attached to the supporting frame 12.

Extending laterally of the frame 12 is a brace member 33. Pivotally attached at 34 100 to this brace member 33 is a bell crank lever, the short arm 35 of which has engagement with the operating rod 30, by means of a pin 36 which normally rests in a recess 37 formed in the edge of the rod 30 (Fig. 7). 105 Pivotally secured to the supporting frame 12 is an arm 38, one end of which is bent to extend parallel and in contact with the edge of the rod 30, and is provided with a recess 39 which is coincident with the recess 37 in the rod 30 at one point in the reciprocating movement of said rod. A spring 40

is attached at one end to the arm 38, and at the opposite end to a stationary part of the supporting frame 12, by means of which the arm is maintained in the position relative to the rod 30 as it is shown in Figure 3.

The long arm 41 of the bell crank lever extends approximately to the center of the tub 42 and has connection with a rod 43 which projects beyond the edge of the supporting member 12. To this rod 43 is pivotally secured an upwardly extending arm or lever 44 fulcrumed to a stationary projection 45 connected with the tub 42 at approximately the middle of its height. This arm or lever has connection with a rod 46 and transmits motion to the agitating mechanism inside of the tub, which mechanism is not here shown in detail as it is of the same form and construction as now used on washers of this kind.

Mounted on a pivot 32 is a bell crank lever 47, the short arm 48 of which is attached to the rod 31. A spring 49 has connection at one end with the rod 31, the opposite end of this spring being attached to the supporting frame 12, the function of this spring being to maintain the lever 47 at either terminal of its movement. When the lever 47 is turned to reversed position as shown in Fig. 7, the tension of the spring 40 will draw the arm 38 against the pivot 36, and when the recesses 37 and 39 are coincident, the pivot 36 will occupy the recess 39, permitting the rod 30 to be reciprocated without transmitting motion to the bell crank lever 35-41.

A vertical shaft 50 supports the crown gear 25 and extends upwardly to the wringer support 51. The wringer 52 is mounted upon said shaft and adapted to be operated through a system of gears (not here shown) whereby it may be operated from the shaft 21 as an independently operable mechanism.

In Fig. 4 I have shown a slightly modified form of mechanism for the operation of the agitator inside the tub. In this instance I provide a shaft 53 which extends through the bottom of the tub and supports the agitator on the opposite end thereof. A pinion 54 is carried on the end of this shaft. Positioned in operative relation with said pinion is a rack bar 55 which has connection at one end thereof with a rocker arm 56, which is pivotally attached at the center thereof to the supporting member 57, and is connected to the lateral members 58 of the frame 12. The opposite end of the rocker arm 56 is pivotally attached to the reciprocating bar 30 from whence the apparatus receives its motion.

It is more common practice to arrange the pinion driving the agitator in the top of the tub as described in Fig. 13, in which case the pinion 57 is supported in the cover 65 of the tub in a housing 58. A rack bar 59

engages the teeth of the pinion 57, which rack bar has connection with the reciprocating rod 46 which is actuated by mechanism heretofore described.

I claim:—

1. An apparatus of the class described, including in combination a supporting frame, a washing mechanism mounted thereon, motor driven mechanism including a driving rod, a cam for reciprocating said rod, a bell crank lever connecting said driving rod with the washing mechanism, and means for throwing said driving rod into and out of engagement with the lever. 70

2. An apparatus of the class described, including in combination a supporting frame, a washing mechanism mounted thereon, motor driven mechanism having connection with the aforesaid mechanism said latter mechanism comprising a driving rod, a bell crank lever having pivotal engagement therewith and with the washing mechanism, and means automatically controlling the operation of the driving rod as it moves into and out of engagement with the lever. 80

25 3. An apparatus of the class described, including in combination the supporting frame, washing mechanism mounted thereon, a motor, a longitudinally reciprocating driving rod, cam actuated mechanism connecting said motor to said rod, a bell crank lever having operative engagement with said driving rod, connecting means between one arm of said lever and the agitator of the washing mechanism, and means for throwing said driving rod into and out of engagement with the bell crank lever. 95

30 4. An apparatus of the class described, including in combination a supporting frame, washing mechanism mounted thereon, driving mechanism, gears having connection with said driving mechanism, a driving rod, a cam positioned eccentrically with respect to one of said gears, and having connection with said driving rod, a bell crank lever, a detachable connection joining said lever to said rod, and a hand lever for actuating said connection whereby said lever is disconnected from said rod. 105

35 5. An apparatus of the class described, including in combination the supporting frame, washing mechanism mounted thereon, driving mechanism, a driving rod operated by the driving mechanism, a bell crank lever having connection with said driving rod for transmitting a reciprocating motion to the washing machine mechanism, and means for disconnecting said driving rod from the lever. 110

40 6. An apparatus of the class described, including in combination the supporting frame, washing mechanism mounted thereon, a driving rod, cam actuated mechanism operating said rod, a bell crank lever regulating the transmission of reciprocating motion 115

from said driving rod to the washing mechanism, a spring having connection with one end of said rod to maintain said rod in operative engagement with said lever.

5 7. An apparatus of the class described including a supporting frame, a washing machine mounted thereon, motor mechanism, a shaft rotated by said mechanism, an eccentric wheel carried by said shaft, a band surrounding said wheel, a lever joined to

said washing machine, an operating rod joined at one end to said band, a detachable connection joining the other end to said lever, and a hand lever for actuating said connection whereby said lever may be disconnected from said motor. 15

In testimony whereof I have signed this specification.

WILLIAM W. WINGER.
